UNITED STATES PATENT OFFICE.

HARRY L. WILLIAMS, OF CHICAGO, ILLINOIS.

AUTOMATIC STOKER.

1,096,877.

Specification of Letters Patent. Patented May 19, 1914.

Application filed October 7, 1912. Serial No. 724,265.

To all whom it may concern:

Be it known that I, HARRY L. WILLIAMS, citizen of the United States, residing at Chicago, in the county of Cook and State 5 of Illinois, have invented certain new and useful Improvements in Automatic Stokers, of which the following is a specification.

This invention relates to improvements in automatic stokers especially of the type 10 signed for use in connection with locomotive boilers though the mechanism is also adapted for use with any type of furnace.

The especial object of the improvements hereinafter described in detail is to provide 15 an automatic stoker in which some of the steam generated in the boiler connected with the furnace to which the stoker is attached will be utilized in feeding the coal to the furnace above the fire bed; also to rotating 20 the grate, and also to stirring the coals on the grate for the purpose of preventing the formation of clinker, and to improve the combustion by introducing the air to the bed of coals.

25 A further object of my invention is to provide mechanism for accomplishing the result set forth which will be simple in construction and therefore easily operated and not liable to get out of order or break down 30 from ordinary use.

A further object is to provide an automatic stoking device in which the ordinary fire door opening is utilized for introducing the coal from the stoker, and to provide 35 means whereby the stoker may be readily disconnected so as to permit access to the feed doorway for hand stoking before steam has been raised in the boiler, or in case accidents should happen to the stoking mechanism which would put it out of commission.

Having the foregoing and other utilities in view which will be apparent to those skilled in the art, I have designed the stoking mechanism illustrated in a preferred 45 form and arrangement in the accompanying drawing but wish to be understood that details may be materially modified without departing from the spirit and essential ideas involved in my invention.

50 Referring to the accompanying drawing:—Figure 1 represents partly in section and partly in side elevation, my improved automatic stoker applied to a locomotive furnace only so much of the latter being 55 shown as illustrates the relative arrangement and connection between the furnace

and stoker; Fig. 2 is an enlarged perspective fragmentary detail of a pawl and its mounting which is used in operating the grate of the furnace; Fig. 3 is an enlarged detail in perspective of the coal passer which forms an important feature of my improved stoker; Fig. 4 is a front elevational view of the lower portion of a locomotive furnace with my stoker applied thereto; Fig. 5 is a fragmentary detail enlarged showing the mounting of the grate of the furnace; Fig. 6 is an enlarged detail of the cam and adjacent members which constitute important parts of the coal agitating means; Fig. 7 is a top plan view of the furnace grate and the coal agitator the walls of the furnace being shown in section; Fig. 8 is a view, partly in section and partly in elevation, of the coal passer and the chute in which it operates.

Referring to the details of the drawing, 9 represents generally a furnace of conventional form, having a front wall 9^a in which is a feed door opening 9^b. At the four corners of the furnace I have provided inclined 80 plates 9^c, the lower edges of which rest upon the lower flange 9^d of the furnace which forms a rim surrounding the grate. The members 9^e serve to deflect the coal within the furnace upon the circular grate 10 and 85 facilitate a more even combustion of the fuel than when the corner spaces are left without such deflecting means. The grate 10 is of circular form and on the lower surface of its periphery has formed inclined 90 teeth 10^a. The grate is also provided with the usual openings 10^b, all of which are clearly shown in Fig. 7.

11 represents the lower portion of the coal chute which is attached to the front wall of the furnace by suitable bolts passing through a wing or extension 11^c. The upper portion of the chute is preferably made detachable as at 11^a with a flange 11^d which overhangs the upper edge of the lower portion of the 100 chute. In the top 11^a is a hopper 11^b adapted to receive the coal from any suitable source of supply either mechanically or manually introduced. If desired the top 11^a may be bolted to the lower portion 11 but I prefer 105 to so arrange it that it may be readily removed. The upper portion 11^a is divided into a curved conduit 11^e by a bottom wall 11^f, as shown in Fig. 8. The side walls of the chute are vertical and parallel. The rear 110 or outer wall is curved in the arc of a circle and the bottom is entirely open.

The coal passer consists of a casting having its outer wall 12 conforming to the arc of the front wall of the chute and provided on its inner side with a stiffening rib 12^a 5 with an upwardly extending arm 12^b near the free end of which is a shaft opening 12^c. The upper portion of the body of the passer is formed with a mouth 12^d bound on its upper and lower sides with lips 12^e, 12^f, said 10 mouth and lips forming essentially a pocket adapted to receive a certain amount of coal from the hopper 11^b and to carry it upwardly and forwardly through the feed doorway 9^b. The passer is mounted to reciprocate in the chute with its walls fitting snugly the side and rear walls of the hopper. Secured to the front wall 9^a of the furnace by bolts 13^a is a vertical plate 13 which is formed with an angular arm 13^b extending 20 rearwardly and is also formed with an extension 13^c which terminates at its lower end in a journal bearing 13^d. A rod 14 is slidably mounted in the arm 13^b and has its upper end connected by a bolt 15^a with the 25 lower end of the piston rod 15 the piston of which is mounted in the usual manner in the cylinder 16, and the latter is supplied with steam from any suitable source and in any approved manner through the pipe 16^a. Pivotally connected with the bolt 15^a is a link 17 which is also pivoted to a crank arm 17^a 30 mounted on a shaft 18 which is journaled in the side walls of the chute 11 and passes through the opening 12^c in the passer 12 so that the rocking of the shaft 18 will reciprocate the passer 12. The lower end of the bar 14 is pivotally connected at 19^a with the upper end of a link 19 the lower end of which is connected with the crank 20 which 35 40 is keyed on the rock shaft 21. The latter shaft is journaled in a bearing 13^a of the plate 13^c and also in the lower ends of brackets 22 which are connected at 22^a with the side wall of the furnace. 45 Pinned on the rock shaft 21 is an arm 23 in the upper free end of which is pivotally mounted the pawl 24 which is so formed and arranged as to engage the vertical face of the teeth 10^a of the grate bar when the 50 arm 23 is rocked in one direction and to drag over the inclined walls of the teeth when said bar rocks in the reverse direction. The relative arrangement of teeth 10^a and pawl 24 is such that at each forward rocking movement of the bar 23 the grate will be partially rotated. 55 Keyed upon the shaft 21 is a cam 25 on the working face of which are formed a series of shallow and rounded teeth 25^a. 60 These teeth frictionally engage a roller 26 mounted in a bracket 26^a which is pendant from a horizontal plate 27. Extending upwardly from the plate 27 are two pairs of legs 27^a the upper ends of which are secured 65 to a segmental plate 28. This plate is pro-

vided in its upper surface with a series of vertical teeth 28^a which are adapted to project through the openings 10^b in the grate 10 when said agitator is raised. The legs 27^a slide loosely in vertical grooves 29^c formed in the side walls of the grate supporting bar 29. This bar is provided with the usual arms 29^a for tilting the grate and is supported from the furnace in the brackets 29^b. The connection between the grate 10 and 75 grate supporting bar 29 is by the usual central stud 29^d.

The relative arrangement of the grate rotating arm 23 and the cam 25 is such that during the rotation of the grate the agitator 80 28 is in its lowermost position as shown in Figs. 1 and 4, so that it will not interfere with the operation of the grate and when the latter is at rest the agitator will be moved upwardly through the engagement of the cam surface 25^a with the wheel 26, the fingers or pins 28^a passing through the grate bar and into the bed of coals above same. As the grate is designed to rotate in the direction indicated by the arrow *a*, shown in 85 Fig. 7, the agitator will act upon the coal soon after it has been delivered to the fire box thus introducing the oxygen necessary to facilitate proper combustion.

The arrangement of the agitator 28 is 90 such that it will not interfere with the dumping of the grate, it being understood that this dumping is effected by throwing the arms 29^a in the direction indicated by the arrows *b*. The pawl 24 with its supporting 95 arm 23 will furnish a support for the forward portion of the grate 10.

In actual practice coal will be conducted to the hopper 11^b by a suitable mechanical conveyer such conveyer, however, forming 105 no part of this invention as the structure is capable of performing all of its functions regardless of the manner in which the coal is introduced to said hopper.

From the construction disclosed and described it will be apparent that if suitable pressure is provided to reciprocate a piston mounted in the cylinder 16 against the load carried by said piston the passer 12 will be reciprocated within the chute 11 and any coal introduced to the hopper 11^b when the passer is in its lowermost position will fall into the pocket 12^d and when the passer is carried to its uppermost position through the arc of its movement the coal within the 115 pocket 12^d will be carried to the feed door opening 9^b and there dropped upon the grate or the bed of coals above the grate.

By suitable devices not necessary to describe the piston will be controlled so as to 120 feed the coal in small quantities at frequent intervals thereby producing the most efficient results from a fuel combustion and steam producing standpoint. As the grate is rotated step by step during the feeding 125 130

of coal to the fire bed, the fuel will be evenly distributed over the fire bed. It will thus be seen that the piston in the cylinder 16 controlled by any fluid pressure either air, 5 water or steam, will operate the three instrumentalities, to wit: the passer 12, the grate rotating members 23, 24, and the coal agitator 28. It will also be seen that if access is desired to the fire bed through the 10 opening 9^b independently of the stoker, the chute section 11^a may be disconnected from the lower member 11 and the opening will be uncovered so that free access may be had thereto.

15 Having thus described my invention, what I claim as new and desire to secure by Letters Patent, is:—

1. In a furnace, in combination with a rotatable grate, means for agitating fuel on the grate, said means comprising a plurality of fingers adapted to be projected upwardly through the grate openings, and means for intermittently projecting said fingers, said means comprising a cam, a 25 rock-shaft operating said cam, and means on said shaft adapted to rotate the grate in a horizontal plane when said fingers are below the grate and at rest.

2. In a furnace, in combination with a rotatable grate, means for agitating fuel on the grate, said means comprising a plate arranged below the central portion of the

grate and having projections extending upwardly therefrom, means for vertically and intermittently reciprocating said plate, said means comprising a cam and a rock-shaft carrying said cam, and means for horizontally rotating the grate when the plate is at rest, said means carried and operated by said rock-shaft.

3. In a furnace, a circular rotatable grate having projections on its under side, a plate arranged below said grate and having upwardly extending projections adapted to enter openings in the grate, means for reciprocating said plate, and means engaging the projections on the grate to rotate the latter, all of said means operable from a common shaft, and power driven means for rocking said shaft.

4. In a furnace, a circular grate, a plate arranged below said grate and having fingers extending upwardly therefrom adapted to be projected through said grate, a rock-shaft, an arm mounted on said shaft and adapted with said shaft to intermittently rotate said grate, and means on said shaft for intermittently operating said plate.

In testimony whereof I affix my signature in the presence of two witnesses.

HARRY L. WILLIAMS.
